(57) **CLAIM**

The ornamental design for a window screen with zipper, as shown and described.

DESCRIPTION

FIG. 1 is a front elevational view of my design, illustrating the zippers together and the screen in a closed position; FIG. 2 is a top front left side perspective view of my design, illustrating the zippers together and the screen in a closed position;

FIG. 3 is a left side elevational view of my design, as shown in FIGS. 1 and 2, the right side being a mirror image thereof; FIG. 4 is a front elevational view of my design illustrating the zippers apart with the screen in a partially opened position showing the resealable fastening means;

FIG. 5 is a top front right side perspective view of my design, as shown in FIG. 4;

FIG. 6 is a front elevational view of my design, illustrating the zippers further apart and the screen rolled into a fastened position exposing resealable fastening means;

FIG. 7 is a top front left side perspective view of my design, as shown in FIG. 6;

FIG. 8 is a left side elevational view of my design, as shown in FIG. 7; and,

FIG. 9 is a top elevational view of my design, as shown in FIG. 7.

The broken lines illustrating an exemplary frame and is environmental structure and is not a part of my claimed design.

1 Claim, 7 Drawing Sheets
